UNITED STATES PATENT OFFICE.

JOHN E. CORNELL, OF CHICAGO, ILLINOIS, ASSIGNOR TO BATES VALVE BAG COMPANY, OF CHICAGO, ILLINOIS, A CORPORATION OF WEST VIRGINIA.

WIRE-TIE-TWISTING DEVICE.

1,177,306.

Specification of Letters Patent.

Patented Mar. 28, 1916.

Application filed January 27, 1915. Serial No. 4,595.

To all whom it may concern:

Be it known that I, JOHN E. CORNELL, a citizen of the United States, residing at Chicago, in the county of Cook and State of Illinois, have invented a certain new and useful Improvement in Wire-Tie-Twisting Devices, of which the following is a specification.

My invention relates to a device for twisting wire ties. Both the device and its use are 10 illustrated in the accompanying drawings wherein—

Figure 1 is a side elevation of the wire tying device with the tie shown in dotted lines; Fig. 2 is a side elevation of a portion 15 of a modified form; Figs. 3, 4, and 5 show ties of different lengths; Figs. 6, 7 and 8 are illustrations of uses of a tie of a given length for tying crossed reinforcing concrete rods of different thicknesses; Figs. 9, 10 and 11 20 are views of the puckered ends of bags of different thicknesses tied by ties of uniform length.

Like parts are indicated by the same characters in all the figures.

25 A is a double spirally threaded rod having the suspending ring B at one end on which the rod is rotatably mounted at C. At the other end of the rod is a hook D, though in the modified form there may be two hooks 30 D¹, D². They are adapted to engage the loops D² on the ends of the ties E.

F is a stop-block movable along the rod and provided with a set-screw G adapted to engage any one of the recesses H on the spiral 35 rails so that the stop-block F may be fixed in any desired position.

J is a handle adapted to slide along the rod but provided with two inwardly projecting pins K and L adapted to engage the spiral 40 rails on the rod so that when the handle is moved the rod with its hook or hooks rotates.

M, M are reinforcing concrete rods of a given diameter; M¹, M¹ a similar arrangement of rods of a larger diameter; M², M² 45 a like arrangement of rods of a still larger diameter.

N, N¹, and N² are bags of progressively increasing size or heaviness of material so as to make bag ends of different sizes to receive 50 the ties.

The recesses H may be arranged in any desired manner and as frequently as may be required along the rod so as to vary the length of the rod by minute increments.

55 I do not wish to be limited to the precise

form, size, proportion and arrangement of the several parts shown, as of course these may be greatly altered without departing from the spirit of my invention, and I wish my drawings to be taken as in a sense dia- 60 grammatic.

The use and operation of my invention are as follows: Wire ties are used for tying bags, securing bundles of material, attaching at their crossing points the rods which are used 65 for reinforcing concrete and for other such purposes. The sizes of the loops formed by such ties therefore greatly differ. In practice it is common to have ties of different lengths for each such purpose and each varying size of securing loop finally to be formed. In other words, the practice is to vary the length of the ties and use a uniformly operating twisting tool. The operator with the tool adapted to make, let us 70 say, three turns, will apply to a given rod crossing or package a wire tie which when it has received the number of turns predetermined by the nature of the tool, will produce a tying loop of the right size. When he 75 passes to the next assembly of parts to be secured if of a different size, he will select the proper tie of a different length. By my invention the tool is itself made adjustable as to the number of twisting turns made and therefore if the tool be set to make five turns, 80 a given tie can be used to secure a particular arrangement of parts. If now the parts be larger as in the case of reinforcing rods, the same length of wire tie can be used if the 85 tool be adjusted to make, for example, three turns. The result is that I greatly reduce the number of sizes or lengths of ties, and indeed a single length of tie could be used 90 practically for all purposes within the range of ordinary experience. The condition is met by the adjustment of the tool. All this 95 is illustrated in the several drawings, and the arrangement is equally applicable to a single hook tool or a double hook tool. The latter when used twists the wires as indicated 100 in Fig. 2.

I claim:

1. A tool for twisting wire ties, comprising a rod having a spiral groove therealong, a hook at one end, a suspending device at the other, a stop adjustably fixable along the grooved portion of the rod, and a slidably handle between the hook and the stop with means to engage the spiral groove. 110

- 2
2. A tool for twisting wire ties, comprising a rod having a plurality of spiral grooves therealong, a hook at one end, a suspending device at the other, a stop adjustably fixable along the grooved portion of the rod, and a slidible handle between the hook and the stop with means to engage the spiral grooves.
3. A tool for twisting wire ties, comprising a rod having a spiral groove therealong, a plurality of hooks at one end, a suspending device at the other, a stop adjustably fixable along the grooved portion of the rod, and a slidible handle between the hooks and the stop with means to engage the spiral groove.
4. A tool for twisting wire ties, comprising a rod having a plurality of spiral grooves therealong, a plurality of hooks at one end, a suspending device at the other, a stop adjustably fixable along the grooved portion of the rod, and a slidible handle between the hooks and the stop with means to engage the spiral grooves.
5. A tool for twisting wire ties, comprising a rod having a spiral groove therealong, a hook at one end, a suspending device at the other, a stop adjustably fixable along the grooved portion of the rod, and a slidible handle between the hook and the stop with a pin to engage the spiral groove. 25
6. A tool for twisting wire ties, comprising a rod having a plurality of spiral grooves therealong, a hook at one end, a suspending device at the other, a stop adjustably fixable along the grooved portion of the rod, and a slidible handle between the hook and the stop with a plurality of pins to engage the spiral grooves. 35

In testimony whereof, I affix my signature in the presence of two witnesses this 23rd day of January 1915. 40

JOHN E. CORNELL
